US0D1028156S

(12) **United States Design Patent** (10) **Patent No.:** **US D1,028,156 S**
(45) **Date of Patent:** **** May 21, 2024**

(54) **TODDLER SLIDE**

(71) Applicant: **Fujian Feelbaby Technology Co., Ltd.**
Ningde Fujian (CN)

(72) Inventor: **Jianli Qi**, Ningde Fujian (CN)

(**) Term: **15 Years**

(21) Appl. No.: **29/927,733**

(22) Filed: **Feb. 6, 2024**

(51) **LOC (14) Cl.** **21-03**

(52) **U.S. Cl.**
USPC **D21/818**; D21/826

(58) **Field of Classification Search**

USPC D21/811, 814, 818-822, 826-827
CPC A63G 21/00-22; A63B 9/00; A63B
2009/006

(57) **CLAIM**

The ornamental design for a toddler slide, as shown and described.

DESCRIPTION

FIG. 1 is a front elevation view of a toddler slide showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is another perspective view thereof.
